EXERCISE DEVICE

Edward J. Campion, 1733 Stevens Drive, Glenview, Ill.

Filed Jan. 17, 1962, Ser. No. 68,343

Term of patent 7 years

(Cl. D34—5)

The single figure is a front perspective view of an exercise device showing my new design wherein the dominant features reside in the portion shown in full lines. The rear surface of the upper panel is planar like the front surface thereof.

This application is a continuation-in-part of my prior copending application Serial Number D. 65,272, filed May 22, 1961, now abandoned.

I claim:

The ornamental design for an exercise device, as shown and described.
